DESIGN FOR A HALL TREE

Roy R. Fulton, Bridgeport, Ohio

Application November 28, 1941, Serial No. 104,373

Term of patent 14 years

To all whom it may concern:

Be it known that I, Roy R. Fulton, a citizen of the United States, residing at Bridgeport, in the county of Belmont and State of Ohio, have invented a new, original, and ornamental Design for a Hall Tree, of which the following is a specification, reference being had to the accompanying drawing, forming part thereof.

Figure 1 is a front elevational view of a hall tree, showing my new design;

Figure 2 is a side elevational view; and
Figure 3 is a top plan view thereof.

I claim:

The ornamental design for a hall tree, as shown.

ROY R. FULTON.
